[57] CLAIM

The ornamental design for a combined writing pad and pencil holder, as shown and described.

DESCRIPTION

FIG. 1 is a top plan view of a combined writing pad and pencil holder showing our new design;

FIG. 2 is a front elevational view;

FIG. 3 is a bottom plan view;

FIG. 4 is a rear elevational view;

FIG. 5 is a side elevational view, the opposite side being a mirror image thereof; and

FIG. 6 is a front perspective view thereof;

FIG. 7 is a front perspective view of a second embodiment of our new design;

FIG. 8 is a top plan view;

FIG. 9 is a front elevational view;

FIG. 10 is a bottom plan view;

FIG. 11 is a rear elevational view; and

FIG. 12 is a side elevational view, the opposite side being a mirror image thereof.
